REFRIGERATION

Peter J. Lammers and Albert F. Laible,
Oakland, Calif.

Application June 5, 1939, Serial No. 277,362

4 Claims. (Cl. 62—89)

This invention is specifically directed to the construction and form of the interior of a refrigerator cabinet and its upper portion or top, as also to the location of the expansion or cooling unit and the results secured through such location. It also involves the location and results derived from the location of the compressor unit as well as the specific form of pockets provided for the cooling and compressor units, and their functions.

In known forms of construction, the cooling unit is placed within the refrigerator in such a position that it occupies space which should be available for storage of foods, while the compressor unit is placed in either a lower or an upper compartment and requires only a small portion of the additional volume added to the refrigerator for its installation, thus useless volume is added to the refrigerator and storage space is occupied by the cooling unit. Also, where glass or other transparent doors are installed, the cooling unit is in plain sight, and it thus becomes plainly apparent that the storage space is definitely limited.

In these refrigerators also, the ceiling of the cabinet is uniform in height throughout the extent of the cabinet and in a plane completely above the top of the cooling unit, thus providing a comparatively large space for warmer air to remain motionless and thus promoting uneven temperatures in different portions of the refrigerator, and thus maximum efficiency cannot be expected nor obtained.

The objects of this invention are as follows:

First: to locate the cooling unit in its entirety above the normal plane of the ceiling, so as to induce circulation throughout all portions of the interior of the cabinet, and to form the pocket in which the cooling unit is mounted in such manner as to promote natural and efficient circulation, and also to form the walls of the pocket in such a manner as to increase this circulation to a maximum.

Second: to locate the cooling unit in a position in which it does not obstruct or take up any of the storage space within the cabinet, so as to provide a maximum volume of storage space.

Third: to form the ceiling of the cabinet with its major portion located in a normal plane at the top of the storage space and to form an inverted pocket upwardly into the ceiling for the cooling unit, with the pocket ceiling being connected to the cabinet ceiling by means of an inclined ceiling portion to promote uninterrupted flow of warmer air to the top of the cooling unit

for its normal circulation downwardly through the cooling unit.

Fourth: to form a pocket in the top of the cabinet complementary to the previously-mentioned pocket for mounting the compressor unit in a position where heated air created through operation of the compressor will be free to dissipate in a normal upward direction, and to provide an inclined floor on one side to promote circulation of cooling air to the bottom of the compressor unit.

Fifth: to mount the compressor unit and the cooling unit in substantially the same horizontal plane so as to maintain the overall volume of the refrigerator at a minimum while providing maximum storage space.

In describing this invention, reference will be had to the accompanying drawing in which:

Fig. 1 is a front elevation of a refrigerator with this invention embodied therein.

Fig. 2 is a longitudinal sectional elevation through the refrigerator showing the invention.

Fig. 3 is a section taken on line 3—3 of Fig. 2.

Fig. 4 illustrates a modified or streamline form of ceiling and top floor construction.

The usual expansion or cooling unit of any suitable type, together with its compressor unit are used with this invention and are indicated respectively at 10 and 11.

The invention consists of a cabinet 12 having 30 suitably insulated front wall 13, rear wall 14, side walls 15 and 16, bottom 17, and ceiling 18, and suitable doors 19 are provided in number sufficient for convenient access to the storage space, according to the length of the refrigerator. The doors are illustrated as glazed, and which is the preferred type of door.

The normal plane of the ceiling lies close to the top of the doors 19 as illustrated, and the space between the ceiling 18 and bottom floor 40 20 is entirely clear of the cooling unit to provide maximum storage space.

The inverted cooling-unit pocket 21 is formed upwardly into the ceiling and has sufficient height to completely house the cooling unit 10 45 so that this cooling unit is located in its entirety above the normal plane 22 of the ceiling 18, and one side wall 23 of this pocket is inclined to promote free and unhampered movement of warmer air to the space 24 above the cooling unit, and forms an inclined continuation of the ceiling 18 connecting with the ceiling of the cooling unit pocket. This inclined wall promotes efficient circulation of air from the space below the normal ceiling and causes the air to flow over 50 55

the cooling unit instead of passing into the sides, and thus the entire cooling unit is effective in cooling the air.

As will be noted, the air passing down through the cooling unit 10 as indicated by the arrows, travels down to the bottom of the cabinet, and as it becomes warmer, it rises in the space toward the side 15 out of the influence of the downdraft, gradually reaching the normal ceiling 18 and continues its movement toward the pocket due to the natural tendency of warmer air to seek a higher level, and due to the fact that this higher level is provided, circulation will continue uninterruptedly from the normal ceiling.

The air moving upwardly close to the wall 15 will naturally move as readily and efficiently toward the cooling unit pocket as that moving through an inside path, and due to the comparative sudden rise at 25 and the natural outward curved sweep of the air at this corner, eddy currents are introduced in the air stream and have a definite effect in setting up air movements throughout the cabinet, and prevent any lack of circulation in the more remote sections, such as the area of juncture of the normal ceiling with the side wall 15.

The air has ample space to move freely along the inclined ceiling portion 23 and to move into the superposed chamber 24, to pass down through the cooling unit, and thus a very efficient system of circulation is provided by the location, form and structure of the cooling unit pocket.

In addition, the cooling unit is completely out of sight, being located in its entirety above the top of the doors 19, and it obviously does not take up any of the normal storage space, providing maximum capacity for storage and cooling of foods or other materials to be refrigerated.

The top floor of the cabinet follows the contour of the ceilings, and a compressor unit pocket is formed at the other end of the refrigerator from that at which the cooling unit pocket is formed, and is similar in shape to the cooling unit pocket except that it is not inverted.

This compressor unit pocket 26 has a floor 27 on which the compressor unit is mounted, and it will be noted that the two units, 10 and 11, are mounted in substantially the same plane, thus reducing the overall volume of the refrigerator. One side wall 28 of the compressor-unit pocket is sloped at the same inclination as the ceiling portion 23 and conveniently formed parallel thereto, and forms a down-draft element for directing cooling air below and about the compressor unit, thus increasing the cooling efficiency, particularly in view of the fact that the escape of heated air is effected in its natural upward direction. Thus the natural flow of cooling air is unhampered and unrestricted, and transfer of the heat from the compressor unit to the refrigerator is substantially obviated.

A streamline modification of the ceiling is illustrated in Fig. 4, the general characteristics of which are similar to the ceiling previously described except that sharp corners are eliminated. The arcuate corners 29 and 30 have real merit, but the sharp corner 25, Fig. 2 is preferred in lieu of the rounded corner 31, Fig. 4, since the sharp corner at this point forms a break in the circulating path and induces eddies which effect more thorough circulation, while the rounded corner promotes a smooth flow of air. Therefore the most desirable arrangement would include the rounded corners 29 and 30 and the sharp corner 25.

It is perfectly obvious that in connection with long refrigerators, the top including the two pockets need only be long enough to house the two units, and that beyond that length the top can be dropped down to the level of floor 21, thus forming a cupola effect on the refrigerator.

In such cases which require rapid cooling, it may be necessary to install a circulating fan in the refrigerator as is customary in commercial types of refrigerators, and in such cases the preferred location in this refrigerator is in a position adjacent to the straight or vertical wall of the cooling-unit pocket, as illustrated at 32, in which case the air will be driven through the cooling unit toward inclined ceiling 23, where the air will be deflected toward the wall 15, continuing about the refrigerator in a direction opposite to that indicated by the arrows for natural circulation, the air ascending along the wall 16 to the fan 32 for re-circulation.

Thus all of the advantages are retained when forced circulation is used; the conservation of space; minimum overall volume of refrigerator with maximum volume of storage space, and thorough circulating effect induced by the inclined wall of the cooling unit pocket.

Obviously the inclined wall has a specific function to perform whether natural or forced circulation is used, and in either case, this inclined wall promotes the very highest circulating efficiency.

It will be understood that variations in construction and arrangement, which variations are consistent with the appended claims, may be resorted to without detracting from the spirit or scope of the invention, or sacrificing any of the advantages thereof.

We claim:

1. In a refrigerator having storage space and a cooling unit; a fan and driving means therefor and associated with said cooling unit; a cabinet having a roof, a ceiling at the top of the storage space and having an inverted pocket having side walls including an inclined wall forming a downwardly diverging pocket, and having a top wall 45 and formed upwardly from the ceiling with said cooling unit and its fan and driving means therefor mounted within said pocket and in its entirety being located above the plane of said ceiling, said fan being located on one side of said cooling unit 50 for forcing warmer air which is normally seeking its higher level, through said cooling unit toward said inclined wall, the air being deflected by the inclined wall angularly downward into the storage space to promote thorough and efficient circulation.

2. A structure is defined in claim 1 in which the roof of said cabinet is formed with a pocket having one side wall formed parallel to the inclined wall of said pocket for the cooling unit and 60 having a compressor unit mounted therein, whereby said cooling unit and the compressor unit are mounted within a height of cabinet top not to exceed that required for the higher of the two units, thus maintaining the overall volume of the 65 refrigerator at a minimum, and in which said inclined side wall directs the natural flow of cooling air free of thermal influence from the compressor to the lower end of the compressor for natural circulation thereabout.

3. A refrigerator comprising; a cabinet having storage space having vertical side walls and a ceiling; a cooling-unit pocket formed upwardly through said ceiling and having one side wall formed as a continuation of one of said vertical 75

side walls, a ceiling and an opposite side wall downwardly inclined from said ceiling and forming a divergent pocket, and a cooling unit mounted in its entirety within said pocket in spaced relation to said one side wall and within the limits of the non-divergent portion of the pocket leaving an upwardly converging pocket between said cooling unit and said downwardly inclined wall for free natural circulation of air upwardly to the space between the top of the cooling unit and the ceiling for the pocket free of thermal influ-

ence from the cooling unit until the air reaches the upper portion of the converging pocket.

4. A structure as defined in claim 3; a fan and driving means therefor mounted between said cooling unit and said one side wall for forcing air through said cooling unit toward said inclined wall; said inclined wall deflecting the forced air angularly downward into said storage space for efficient circulation. 5
